No. 836,429.

PATENTED NOV. 20, 1906.

D. ALLEN.

ROLLER BEARING.

APPLICATION FILED DEC. 29, 1905.

UNITED STATES PATENT OFFICE.

DELOS ALLEN, OF LOS ANGELES, CALIFORNIA, ASSIGNOR TO THE ANTI-FRICTION JOURNAL BOX COMPANY, OF LOS ANGELES, CALIFORNIA, A CORPORATION OF CALIFORNIA.

ROLLER-BEARING.

No. 836,429.

Specification of Letters Patent.

Patented Nov. 20, 1906.

Application filed December 29, 1905. Serial No. 293,709.

To all whom it may concern:

Be it known that I, DELOS ALLEN, a citizen of the United States, residing at Los Angeles, in the county of Los Angeles and State 5 of California, have invented new and useful Improvements in Roller-Bearings, of which the following is a specification.

This invention comprises a roller-bearing provided with bearing-rollers and separating- 10 rollers mounted around the spindle of an axle, said rollers being held in place on the spindle by tracks and rings, which prevent accidental removal of the rollers, said tracks being mainly integral with the spindle.

15 An object of the invention is to provide a strong and simple bearing of this kind.

Another object is to provide such a bearing that can be readily assembled and taken apart although solid retaining-rings are used.

20 In carrying out this invention the spindle of an axle may be turned down, leaving tracks thereon integral with the spindle. The tracks may be simply integral with the spindle in the main portions of said tracks, a segment 25 of the track being cut away and a detachable segment inserted in the place thereof, as will be hereinafter more fully set forth.

In some cases the tracks may be solid and 30 integral with the spindle throughout the full circumference of the spindle. In such cases open rings of some known kind may be used to retain the rollers on the spindle.

The accompanying drawings illustrate the 35 invention.

Figure 1 is a fragmental sectional view illustrating the invention as applied in the hub and on the axle of a vehicle. $x^1 x^1$ in other views indicate the line of section. Fig. 2 is a section on line $x^2 x^2$, Fig. 1. Fig. 3 is a section on line $x^3 x^3$, Fig. 1. Fig. 4 is an enlarged fragmental sectional view on line x^4 , Fig. 1, showing the detachable block of the track. Fig. 5 is a fragmental plan showing the track-block in place in the track. Fig. 6 is a side 45 view of the track-block detached from the track. Fig. 7 is a plan view of the track-block detached. Fig. 8 is a sectional view on line $x^5 x^5$, Figs. 4, 5, 6, 7, showing the track-block in place. Fig. 9 is a sectional detail of 50 the end-thrust bearing. Fig. 10 is an end view of the roller-bearing in the process of assembling with the form of track shown in Fig. 1, the bearing-rollers all being shown in

place as they appear when the last one there- 55 of has just been inserted. Fig. 11 is an end view showing the parts in position during the process of inserting the separating-rollers. Fig. 12 is an end view showing the bearing after the rollers are in position, showing method of inserting the screw in the block. 60 Figs. 13 and 14 are views of the stripped bearing and separating rollers, respectively. Fig. 15 is a view of the spindle with the tracks integral therewith throughout. Fig. 16 is a section on line $x^{16} x^{16}$, Fig. 15. 65

1 designates an axle-spindle. 2 is the bearing-box; 3, the large bearing-rollers between the axle and box, said bearing-rollers being provided with notches 4 to receive tracks 5, that extend in the form of annular shoulders 70 or flanges around the spindle to prevent longitudinal displacement of the bearing-rollers 3 relative to the spindle.

6 designates the separating-rollers to separate the bearing-rollers 3 from each other. 75

7 designates revolving rings in the notches 4 of the bearing-rollers 3, said notches 4 being in the form of annular grooves containing said rings 7 and the tracks 5. Each track may be constructed with a detachable section or block 8, dovetailed in a gap 9 and fastened by a screw 10, screwed into the journal. 80

In order to allow the insertion of the block after the rollers are assembled around the journal and within the revolving rings 7, one 85 large roller 3 and one small roller 6 are stripped at each end to form a smooth spindle, as 11 12, that will not obstruct the placing of the section of track in its place after the rollers are inserted, as will be hereinafter 90 explained.

In case the track is sectional, as illustrated in Figs. 1 to 12, the blocks 8 will be detached for the purpose of assembling, leaving open gaps 9 in the tracks 5. Then the rings 7 will 95 be placed around the journal 1 at the tracks, respectively, and the large bearing-rollers will be inserted one by one endwise through the gaps 9 inside the rings until the full quota of large rollers has been inserted one at a time through the gap and brought under the revolving rings. Then two of the large rollers at the gap will be spread apart, and a small roller 6 will be inserted through the gap under the ring, and then the large roller, with 100 a separating-roller at one side of the gap, will 105

be rolled over beyond the gap, whereupon another small roller may be inserted through the gap and under the rings. Then another large roller will be rolled past the gap toward 5 the last-inserted small roller, and then another small roller will be inserted, as before, and so on until the full quota of both large and small rollers has been inserted through the gap and under the rings. Then the 10 stripped large and small rollers will be brought together at the gap, and the blocks 8 will be slipped along the stripped spindles 11 12 and into place to close the gap 9 and will then be fastened by the screw 10, which can 15 be inserted through the space between the stripped spindles 11 12.

When the blocks for both tracks are thus secured, a roller-bearing has been formed which is firmly connected with the axle-spindle 20 1 and is ready for the reception of the hub 13, having box 2, which can be pushed on and taken off at pleasure without disarranging the rollers.

In the drawings, 14 designates thrust ball-bearings at the ends of the sleeve of the hub 25 13. 15 designates bearing-rings at the ends of said sleeve to engage the balls 16 of such bearing.

17 and 18 designate dust-caps at the ends 30 of the hubs to prevent dust from getting into the bearing.

It will be noted that by the device shown the bearing-rollers bear on the spindle inside and outside the tracks, except in case of 35 the sectional tracks, where the bearing-roller provided with the two spindles will bear only between the tracks.

In case the tracks are integral throughout with the axle the retaining-rings may be of 40 a sectional character, having the sections hinged or otherwise secured together so that the rings can be opened. As such rings are

known to the art and are not a part of my invention, I have not illustrated the same.

What I claim is—

45 1. A spindle provided with a plurality of annular flanges mainly integral therewith, bearing-rollers and separating-rollers grooved to receive the flanges, and rings in said grooves for holding the rollers from displacement from the flanges.

1. A spindle provided with a plurality of annular flanges, a section of each flange being integral with the spindle and another section being detachably fastened to the spindle, 55 bearing and separating rollers grooved to receive the flanges, a bearing and a separating roller each provided with spindles at the ends to receive the flanges; and rings in said grooves and outside said roller-spindles for 60 holding the rollers from displacement from the flanges.

3. A spindle provided with a plurality of annular flanges, a section of each flange being integral with the spindle and another section 65 being dovetailed therein, screws securing the dovetail sections in place, bearing and separating rollers grooved to receive the flanges, a bearing and a separating roller terminating in spindles outside said flanges, and rings in 70 said grooves and outside said spindles.

4. A roller-bearing comprising cylindrical rollers having grooves at their ends and a spindle provided with tracks or flanges at each end adapted to fit in said grooves, portions of said tracks or flanges being removable.

In testimony whereof I have hereunto set my hand, at Los Angeles, California, this 22d day of December, 1905.

DELOS ALLEN.

In presence of—

JAMES R. TOWNSEND,
JULIA TOWNSEND.
